UNITED STATES PATENT OFFICE

ALFRED H. HOTOPP, JR., OF CALDWELL, NEW JERSEY, ASSIGNOR TO WIRED RADIO, INC.,
OF NEW YORK, N. Y., A CORPORATION OF DELAWARE

SYSTEM FOR REDUCTION OF EXTRANEous ELECTRICAL EFFECTS

Application filed August 18, 1930. Serial No. 475,870.

My invention relates in general to radio transmitting and receiving systems and specifically relates to wired radio systems employing means to reduce extraneous electrical effects.

It is well known in radio to transmit and receive the audio frequency range by means of a carrier and both side bands, as well as by means of a carrier and single side band. However, I am not aware that any system has been heretofore proposed for transmitting, over wires, the entire audio frequency range by means of the carrier and one of the side bands while transmitting a predetermined portion of the same audio frequency range by means of both side bands in order to reduce extraneous electrical effects in reception.

One of the objects of my invention consists in producing a system for wired radio transmission and reception in which means are provided to substantially reduce extraneous noises and electrical effects.

Another object of my invention consists in providing a system for reduction of extraneous electrical effects comprising a wired radio broadcasting system in which the carrier is transmitted together with both of the side bands for a predetermined portion of the transmission frequency range and only one of the side bands for the remainder of the transmission range with proper compensation in the receiver to obtain uniform reception.

These and other objects I accomplish as hereinafter disclosed, reference being had to the accompanying drawings in which:

Fig. 1 is a graphical representation of a theoretical filter for transmission of carrier and both side bands.

Fig. 2 is a graphical representation of the transmission response of a filter used in my invention.

Fig. 3 is a graphical representation of the characteristics of a receiver used in my invention.

Fig. 4 is a schematic representation of the electrical organization of one embodiment of my invention.

In the system of wired radio broadcasting

in which modulated carrier frequency currents are impressed upon wire lines such as light and power distribution networks, it has been found that, that under certain conditions, extraneous modulation of the carrier will sometimes occur in the transmitting medium. This extraneous modulation, when it occurs, is evidenced at the output of the receiver by a hum which is ordinarily composed of frequencies principally below a thousand cycles.

It is well known that devices having non-linear voltage current characteristics will demodulate modulated waves and that the reproduced component is twice as great when the device is supplied with waves composed of the carrier and both side bands than when supplied with waves composed of the carrier and only one side band. For example, a space discharge detector tube operating on the square law will give a reproduced component equal to $KC^2S \cos(\phi t + \theta)$ when carrier and both side bands are impressed upon it, and a reproduced component equal to $\frac{1}{2}KC^2S \cos(\phi t + \theta)$ when carrier and only one side band are impressed upon it. It is therefore evident, then, that for a definite value for carrier C and modulation K, carrier and single side band transmission will require greater response in the receiver, to produce a given output, than when carrier and both side bands are transmitted. It is therefore obvious that the transmission and reception of carrier and both side bands is much more satisfactory from the standpoint of increased ratio of desired signal to unwanted noise and extraneous electrical effects. However, to transmit carrier and both side bands necessitates the use of a frequency space substantially double the frequency width of that required for carrier and only one side band. My invention contemplates transmitting the carrier together with both side bands for a relatively small portion of the transmission frequency range and in which extraneous modulation occurs, only one of the side bands for the remainder of the transmission frequency range.

Fig. 1 represents the transmission curve

over a certain frequency band for an ideal filter responsive to carrier and both side bands. The upper and lower cut-off frequencies are represented by f_2 and f_1 respectively, the high frequency band for transmission of carrier and both side bands being therefore equal to $f_2 - f_1$, the carrier frequency being represented by "c". The upper side band is equal to $f_2 - c$, while the lower side band is represented by $c - f_1$. As before stated, the extraneous or hum modulation frequencies are usually below one thousand cycles and are therefore restricted to a relatively small percentage of the total audio frequency range. The maximum limit of the extraneous modulation frequency for the upper side band is represented by f_4 in Fig. 1, while the maximum limit for the extraneous frequencies for the lower side band is represented by f_3 . The frequency range for the extraneous modulation for carrier and both side bands is therefore represented by $f_4 - f_3$.

As before pointed out, the transmission of the carrier and both side bands effectively reduces, at the receiver output, such extraneous modulations, since the ratio of the desired signal to extraneous electrical effects is greater for transmission and reception of carrier together with both side bands than for carrier and one of the side bands for a given carrier input and degree of signal modulation. However, the transmission of both side bands above the extraneous modulation range is not necessary, since a satisfactory signal to noise ratio in this portion of the frequency spectrum is obtainable with single side band transmission. Since it is of great importance to conserve space on frequency transmission channels, I therefore, according to my invention, produce a type of filter for both transmission and reception and which has a theoretical transmission curve similar to that shown in Fig. 2, which is evolved from Fig. 1. The upper cut-off frequency remains f_2 as in Fig. 1, but the lower cut-off frequency becomes f_3 with the carrier "c" in the same relation. The frequency range therefore equals $f_2 - f_3$, the entire audio frequency range being transmitted and received over the upper side band $f_2 - c$, while the lower side band, represented by $c - f_3$, is used to transmit the audio frequency only over the extent of the extraneous modulation frequencies.

Fig. 4 represents a wired radio transmission and reception system employing my invention. Light and power lines 1 extend from a light and power current source 2. Such light and power current source and lines 1 are indicative of a normal commercial light and power distribution network. An oscillator 3 provides carrier frequency currents to the power amplifier 4. This

carrier frequency current is modulated by the modulator 5 under control of a microphone 6. The modulated carrier frequency is then passed through filter 7 which attenuates all frequencies other than those lying within the range theoretically represented by $f_2 - f_3$ in Fig. 2, the constants of the filter 7 being of a value such as to pass frequencies within the range $f_2 - f_3$. The output from the filter 7 is impressed upon the lines 1 through capacitative couplings 8. A filter 9 is connected through a capacitative coupling 10 to the line 1. This filter 9 has a transmission response similar to that of filter 7 and which is graphically depicted in Fig. 2. The frequencies passed by filter 7 are likewise passed by filter 9 and fed to the receiver 11. The receiver 11 has constants of a value such as to produce uniform output signal level over the entire audio frequency range thus compensating for the increased response which would otherwise occur due to the transmission of carrier and both side bands for the low audio frequencies. Referring to Fig. 3, the curve "M" graphically represents the characteristics of the receiver system of my invention in terms of output signal level over the audio frequency range. It will be noted that the receiver is designed to be less responsive for that part of the audio frequency range transmitted by means of carrier and both side bands than for that part of the audio frequency range transmitted by carrier and one side band. This compensation for the greater response which would otherwise be present due to transmission of the low audio frequencies by means of carrier and both side bands produces a uniform effective output signal level for the receiver graphically represented by the curve "O". If a receiver intended for reception of the entire audio frequency range by means of carrier and both side bands were employed in the system of my invention, the output signal level over the audio frequency range would be non-uniform as graphically represented by the curve "N". It is evident that the differences of the ordinates of the curves "O" and "M" are representative of reduction in extraneous and undesirable hum and noise due to extraneous modulation of carrier. The actual reduction of extraneous noise and electrical effects is represented by the shaded area in Fig. 3.

It will now be obvious that I have provided an effective system for substantially reducing the resultant hum or noise due to extraneous modulation in the transmission and reception of modulated high frequency currents by employing a combination of carrier together with double side band transmission and carrier together with single side band transmission with receiver response compensation. The exact circuits

to be used in my system are well known in the art, and it is also well known that the constants of these circuits can be adjusted to produce the results described and which 5 in combination constitute my invention. It will, of course, be understood that changes can be made in my system without departing from the intended scope of my invention. I do not therefore desire to limit myself to the foregoing except insofar as 10 pointed out in the appended claims.

What I claim as new and original and desire to secure by Letters Patent of the United States is:

15 1. A system for radio transmission comprising, a source of carrier current modulated at audible frequencies, means adapted to transmit carrier and one side band of said modulated current for the entire audio frequency 20 range and carrier and the other side band of said modulated current for a predetermined portion of the audio frequency range in which extraneous modulation occurs and receiver means adapted to receive 25 said transmitted current, said receiver means being adapted to produce a uniform output over substantially the entire audio frequency range.

2. A system for the reduction of extraneous 30 electrical effects comprising, a source of modulated high frequency current, means adapted to transmit a predetermined portion of the audio frequency range by means of carrier and both side bands of said current, while transmitting the remainder of the audio frequency range by means of said carrier and single side band, and receiving means adapted to receive said transmitted frequencies, said receiving means being less 35 responsive to said carrier and double side band frequencies than to said carrier and single side band frequencies.

3. A hum elimination system comprising, in combination, a source of high frequency 45 current, means adapted to modulate said current over the audio frequency range, means adapted to transmit carrier and both side bands of said modulated high frequency current for a predetermined portion of 50 said audible frequency range while transmitting said carrier and single side band for the remainder of said audible frequency range, and receiving means adapted to receive said transmitted currents, said receiving 55 means being less responsive to currents at frequencies within the range in which said carrier and both side bands are transmitted than to currents at frequencies within the range in which said carrier and single 60 side band is transmitted.

4. In combination with a wired radio broadcasting system in which modulated high frequency currents are impressed upon light and power lines, a hum elimination 65 system comprising, a source of modulated

high frequency currents, means adapted to transmit carrier and double side bands of said current for a predetermined part of the audio frequency range while transmitting carrier and single side band for the remainder of said frequency range, and receiving means, said receiving means being less responsive to currents at frequencies within the range in which said carrier and double side bands are transmitted than to currents at frequencies within the range in which said carrier and single side band are transmitted.

5. A system for reduction of extraneous electrical effects comprising, a source of modulated high frequency current, wire lines, means adapted to transmit over said wire lines carrier and double side bands of said modulated high frequency current for a predetermined portion of the audible frequency range while transmitting carrier and single side band of said modulated high frequency current for the remainder of said audible frequency range, and receiving means for said transmitting current, said receiving means being less responsive to currents at frequencies within the range in which said carrier and double side bands are transmitted than to currents at frequencies within the range in which said carrier and single side band are transmitted.

6. A system for reduction of extraneous electrical effects in accordance with claim 4 but in which said carrier and double side bands are transmitted over a smaller portion of the audio frequency range than said carrier and single side band.

7. A system for reduction of extraneous electrical effects comprising, a source of commercial light and power current, wire lines extending from said source, a source of modulated high frequency current, means adapted to impress upon said wire lines carrier and both side bands of said modulated high frequency current for a predetermined portion of the audible frequency range while impressing carrier and single side band for the remainder of said audible frequency range, and receiving means connected to said wire lines and constructed to receive said impressed currents with substantially uniform reproduction of the audible frequency range.
